UNITED STATES PATENT OFFICE.

ARTHUR W. WALKER, OF MALDEN, MASSACHUSETTS.

DESIGN FOR A CASING-RING FOR FURNACES.

SPECIFICATION forming part of Design No. 26,291, dated November 17, 1896.

Application filed October 7, 1896. Serial No. 608,178. Term of patent 14 years.

To all whom it may concern:

Be it known that I, ARTHUR W. WALKER, a citizen of the United States, residing at Malden, in the county of Middlesex, State of Massachusetts, have invented a new and original Design for a Casing-Ring for Furnaces, of which the following is a specification, reference being had to the accompanying drawing, forming part thereof.

10 The drawing represents in perspective a casing-ring illustrating my design.

The leading feature of my novel design for a casing-ring for furnaces consists in a narrow annular body with an outwardly-extended 15 upturned ear thereon.

As shown in the drawing, the casing-ring consists of a narrow annular body a , having on its outer face an outwardly-extended up-

turned ear b , projecting laterally beyond the body a .

The body a is shown as having a cylindrical inner face a' , and an annular rib or flange a^2 on its outer face between its top and bottom edges, the rib or flange terminating at the sides of the upturned ear b .

Having fully described my novel design, what I claim is—

The design for a casing-ring for furnaces, substantially as herein shown and described.

In testimony whereof I have signed my name to this specification in the presence of two subscribing witnesses.

ARTHUR W. WALKER.

Witnesses:

JOHN C. EDWARDS,
EMMA J. BENNETT.
